Specification for Design.

Patented Feb. 24, 1914.

Application filed October 25, 1913. Serial No. 797,350. Term of patent 7 years.

To all whom it may concern:

Be it known that I, FERDINAND P. SCHOENHARDT, a citizen of the United States, residing at Meriden, in the county of New Haven and State of Connecticut, have invented a new, original, and ornamental Design for Lighting-Fixtures, of which the following is a specification, reference being had to the accompanying drawings, forming part thereof.

In these drawings, Figure 1 is a view in side elevation of a lighting fixture embodying my design, part only of a suspend-

ing means being shown. Fig. 2 is a bottom plan view of the lighting fixture shown in Fig. 1.

What I claim is:

The ornamental design for a lighting fixture as shown.

FERDINAND P. SCHOENHARDT.
